UNITED STATES PATENT OFFICE

165,354

COMBINATION RADIO AND CLOCK

Armand S. Zucker, Chicago, Ill., assignor to
Mitchell Manufacturing Company, Chicago, Ill.

Application April 3, 1951, Serial No. 14,697

Term of patent 3½ years

(Cl. D56—4)

To all whom it may concern:

Be it known that I, Armand S. Zucker, a citizen of the United States, residing at Chicago, Cook county, State of Illinois, have invented a new, original, and ornamental Design for a Combination Radio and Clock, of which the following is a specification, reference being had to the accompanying drawing, forming a part hereof.

Fig. 1 is a front elevational view of a combination radio and clock, showing my new design.

Fig. 2 is an end view thereof.

Fig. 3 is a top plan view thereof.

The dominant features of my design reside in that portion shown in full lines in the drawing.

I claim:

The ornamental design for a combination radio and clock, as shown and described.

ARMAND S. ZUCKER.
